UNITED STATES PATENT OFFICE.

MARK HAMM, OF STOCKTON, CALIFORNIA.

HOT AND FORCE BLAST CUPOLA.

SPECIFICATION forming part of Letters Patent No. 354,899, dated December 28, 1886.

Application filed November 12, 1885. Serial No. 182,543. (No model.)

To all whom it may concern:

Be it known that I, MARK HAMM, a citizen of the United States, residing at Stockton, in the county of San Joaquin and State of California, have invented certain new and useful Improvements in Hot and Force Blast Cupolas, of which the following is a specification, reference being had therein to the accompanying drawings.

10 The invention has for its object improvements in means or apparatus employed in the manufacture of steel; and it consists in the arrangement and combination of parts, which will be more fully described hereinafter.

15 That my said invention may be clearly understood and readily carried into effect, I will proceed, aided by the accompanying drawings, fully to describe the same.

In the drawings, Figure 1 is an elevation 20 showing the main features of my invention, one of the cupolas and the superheated-air chamber being in vertical section. Fig 2 is a section of the superheated-air chamber. Fig. 3 is an elevation of the converter through line 25 *x x*, Fig. 1. Fig. 4 is a section of the superheated air-chamber and one of the cupolas, through line *x x* of Fig. 1, and showing a top view of the converter. Figs. 2, 3, and 4 are on a larger scale than is Fig. 1. Fig. 5 is a 30 top view of shell *h*. Fig. 6 is a vertical section of the same.

In all the figures like parts are marked with similar letters of reference.

In employing my invention I preferably 35 erect a platform, *A*², supported upon suitable pillars, *A'*. Upon this platform I place at each side a cupola-furnace, both of the same construction, but which, for convenience, I separately designate—*A* being the left-hand cupola 40 and *W* the right-hand cupola. These cupolas are constructed of plates of boiler-iron riveted together, having their insides lined with fire-brick and being provided with removable tops *D* and with blast-boxes, *F*, constructed 45 as and for the purposes as will be hereinafter shown. Between these cupolas I place a chamber, *I*, for the purpose of making therein a supply of superheated air. This chamber contains a series of elbow-pipes, *L*, eight in number, their sixteen feet being fixed to horizontal step sections of piping, *M O P Q*, suitably secured to the floor of the chamber *I*. Between each of the feet of the pipes *L* in the sections *M O P Q* is a stop, which causes the air to course through the entire series of the 55 pipes *L* continuously. The tops of the pipes *L* are secured together by an iron stud, *L'*, which is perforated with suitable holes admitting set-screws, *L*², whose threaded ends screw into threads cut in the tops of the sections of the 60 pipes *L*. This chamber *I* is connected to the cupolas *A* and *W* by elbow-shaped pipes *E* at its top on each side, through which the flame passes, as will be shown, from the tops of the cupolas *A* and *W* into the upper part of the 65 chamber *I* into direct contact with the pipes *L*. The superheated air from the chamber *I* is forced into the blast-boxes *F* of the cupolas *A* and *W* by means of the following-described 70 connecting-pipes—viz., a pipe, *Y*, which has its final outlet in a converter, *a*, as will be shown, the flow into such converter being controlled by a valve, *K*, is connected with the step pipe-section *M*. Into this pipe *Y* is fixed a vertical elbow-pipe, *N*, the upper end of 75 which is connected with a horizontal pipe, *J*, which extends across the chamber *I* and empties at its respective ends into the blast-boxes *F* of the cupolas, the flow into which is controlled by valves *J*, (only one of which is 80 shown in the drawings.)

The blast-boxes *F* are of the following construction: The cupolas are preferably twelve feet high. About two feet from their base they are enlarged about twelve inches horizontally for a space of about ten inches vertically. Inside of this enlargement is a deflector, *U*, riveted to the side of the cupola, and having secured to it a wedge-shaped plate, *V*, to equalize the flow of the air beneath the lower edge 90 of the deflector *U*. The superheated air from the pipe *J* enters the blast-box *F*, and evenly flows by means of the deflector *U* and equalizer *V* beneath the edges of the former, and enters the cupola through inlets *h*, formed by a hollow cast-iron flange, *h'*, hub-shaped, about the circumference of the shell of the cupola, the lower edge of which is curved upwardly, so that the air may strike evenly and at the center of the cupola.

100 The chamber *I* is provided with a damper consisting of a stack, *S*, opening at its bottom

into the chamber, and having a cap or top, T, at its apex, operated by a lever.

The tops of the cupolas are open, having covers or caps, D suspended by chains from 5 davits C, and reached by the operator from a platform, B, secured to the sides of the cupolas.

The cupolas at their bottoms are supplied with a tap, H, for drawing off the molten metal; also, with an eyeglass, G, for observing the 10 condition of the metal under process.

The pipe Y, heretofore referred to, is connected with a converter, a, mounted upon standards d, and having its position controlled by a ratchet-gear, e, engaging with a ratchet having a handle, f, with a square end admitting a wrench, so as to change the converter vertically for the purpose of cleaning it out. The pipe Y is connected to the section-pipe i of the converter by a coupling, j, the end of the pipe 20 i having male threads engaging with the female threads of the coupling. It is also supplied with a tap, g, for drawing off the metal for the purpose of running it into bars.

In the event the usual method of providing 25 heat, as will be described, is not found sufficient, a furnace of any ordinary construction may be built at the rear of the chamber I, and an auxiliary fire therein provided, increasing the heating properties of the chamber I.

Having described the construction of my 30 hot-blast cupola, hot-air chamber and their connections, and internal and external machinery, I will now describe the method of operating the same for the purpose of producing the 35 best quality of cast-steel and of pig-iron at a minimum cost.

I first place suitable igniting material in the bottom of each cupola and ignite the same 40 through the tap-hole. When such material is afame I fill each cupola with a suitable quantity of coke, removing the caps D for such purpose. When the coke is at a white heat I place in the cupola A a charge of pig-iron or other mixture, and in the cupola W a charge 45 of raw iron ore. Air is then admitted into pipes L of the chamber I, being forced through the inlet-pipe O'. The flames from the cupolas enter the chamber I through the pipes E and heat the pipes L to a cherry-red, heating the 50 air flowing through them to a high degree. It then flows through pipe R into the cupolas, and by means of the deflectors U and equalizers V flows evenly through the inlets h and comes in contact with the material itself at a center, 55 by reason of the curved lower edge of the shell h'. This curved lower edge of the shell h' prevents the superheated air from making contact with the brick lining of the cupola, thereby saving it from burning out as soon as 60 it does in other styles of furnaces. The damper T controls the degree and quantity of hot air in the chamber I. When the material in the cupola A is sufficiently melted, the entire blast is concentrated (by turning off the 65 valves J at the ends of pipe R, leading into cupola A) upon the ore in cupola W, which, when sufficiently melted, is tapped and drawn

off and molded into pigs of cast-iron. When this is accomplished, the metal in the cupola A is tapped and run off into the converter a, 70 and the entire hot-air blast from the chamber I is concentrated upon it, the valves J of pipe R being closed for the purpose and the valve K of pipe Y being opened, and the connection of pipes Y and i being made by the 75 coupling j. The molten metal in the converter a is freed by the blast from all impurities—such as carbon and phosphorus—and a product left, consisting of the most refined quality of steel, fit to be rolled into bars of any kind. 80

It will readily be seen that I make a most economical disposal of the fuel I employ, and produce a maximum result at a minimum cost.

I am aware that it is not new to employ, in connection with a cupola-furnace, a chamber 85 into which the products of combustion pass, and in which are arranged pipes which are heated by the products of combustion, and in which the air passing through the pipes is heated and then fed to the furnace, and this I 90 disclaim. My invention differs from furnaces of this kind in a platform upon which the cupolas A W and chamber I are placed, the two cupolas being connected together by the pipe R, and the air-supply pipes being passed 95 through the chamber and then connected to a converter in position under the platform. Each of the cupolas is provided with a blast-box provided with deflectors and equalizers and openings through which the hot blast enters 100 the cupolas, the connecting-pipe R being made to pass through the chamber I and connected to the other pipes placed therein.

Having described my invention, what I claim as new is—

1. The chamber I, provided with the series 105 of vertical pipe-sections L, secured to the horizontal step sections M O P Q, suitably secured to the floor of the chamber I, and at their tops secured by the iron stud L' and set-screws L', and having the pipe S and damper T, in combination with the cupola-furnaces A and W, being connected therewith by the upper pipes, E, and lower pipe, R, the pipe R being provided with suitable valves, each furnace 110 being provided with a blast-box, F, containing the deflector U, the equalizer V, and shell h', having the inlets h, and curved lower edge, all operating substantially as set forth and described. 120

2. In a blast apparatus, the combination, substantially as described, of the chamber I, containing the series of pipes M O P Q L, the connecting-pipes E E R, the cupola-furnaces A W, the discharging-pipe Y, the converter a, 125 the platform A', and the pillars A'.

3. The cupola-furnaces A W, provided with the blast-boxes F, containing the deflectors U, the equalizers V, and shell h', having the inlets h for the passage of the hot air into the furnaces, 130 in combination with the pipes E and R, the ends of the latter of which are adapted to discharge the hot air from the chamber I into the blast-boxes F, and the ends of the former of

which are adapted to permit the flow of the flame from the furnaces into the chamber I, the chamber I and furnaces A, W being suitably mounted on platform A², supported by 5 pillars A', said chamber I being provided with a pipe, Y, for conducting the blast into a converter, a, all substantially as set forth.

In testimony whereof I affix my signature in presence of two witnesses.

MARK HAMM.
